United States Patent Office.

ISRAEL BAKER, OF TOMAH, WISCONSIN.

Letters Patent No. 104,096, dated June 14, 1870.

IMPROVED WASHING-MACHINE.

The Schedule referred to in these Letters Patent and making part of the same.

To all whom it may concern:

Be it known that I, ISRAEL BAKER, of Tomah, in the county of Monroe and State of Wisconsin, have invented a new and useful Improvement in Washing-Machines; and I do hereby declare that the following is a full, clear, and exact description thereof, which will enable others skilled in the art to make and use the same, reference being had to the accompanying drawing forming part of this specification.

Figure 1 is a detail sectional view of my improved machine, taken through the line x x , fig. 2.

Figure 2 is a top view of the same.

Similar letters of reference indicate corresponding parts.

My invention has for its object to furnish an improved washing-machine, which shall be simple in construction and effective in operation, and which may be manufactured and sold for a small amount; and

It consists in the construction and combination of the various parts of the machine, as hereinafter more fully described.

A are the ends of the machine, which are vertical, and which have legs, a' , formed upon or attached to them, of sufficient length to raise the machine to a convenient height.

The ends A , upon their inner sides, have circular grooves formed in them, to receive the edges of the thin board or boards B that form the sides and bottom of the machine, which is bent into circular form, as shown in fig. 1.

Rubber packing, C , is placed in the bottom of the groove in the ends A , for the edges of the board B to rest upon to make the joints tight, and at the same time to prevent the boards B from being cracked or injured by shrinking or swelling, as they would be if driven into said grooves.

The ends A and boards B are secured to each other by the long bolts and nuts D , which pass through the ends A , and extend along the outer sides of the boards B , as shown in figs. 1 and 2.

E is a rubber formed by attaching three or more polygonal rollers to a frame, which rubber is pivoted at the lower ends of its end-bars to the ends A by pins passing in through said ends.

The upper part of the rubber E is held forward by the coiled or equivalent spring F , the rear end of which is attached to the said board B , and the forward end of which is attached to the rear side of the upper part of the frame of the said rubber E .

G are the side boards of the movable rubber, which are pivoted to the ends A by pins, the upper parts of which are bent forward to serve as levers for operating the machine, and are connected at their ends by a round or bar, H , which serves as a handle.

The bent part or levers of the sides G are strengthened and held in position by the braces I , as shown in fig. 1.

The lower parts of the sides G are connected and held in their proper relative positions by the cross-bars J , the lower one of which is made somewhat wedge-shaped, and is so arranged that its edge may move along the inner surface of the board B , to tend to lift the clothes away from the bottom of the machine as they are being carried forward by the rubber.

K are three or more polygonal rollers, the ends of which are pivoted to the sides G , and which are so arranged that each lower roller may be a little in advance of the succeeding one, as shown in fig. 1.

By this construction, as the clothes are carried forward by the movable rubber, the upper part of the rubber E yields, and the clothes are rolled, pressed, and rubbed by and between the rollers, and, as the movable rubber moves back, the clothes fall back in the water, turn over, and are opened out, so that a different part of the clothes will be operated upon at each forward movement of the said rubber.

Having thus described my invention,

I claim as new and desire to secure by Letters Patent—

The washing-machine formed by the combination of grooved ends A , bent board or boards B , bolts D , rubber E , spring F , and movable centrally-pivoted rubber G I J K , all constructed and arranged as shown and described.

ISRAEL BAKER.
